CLAIM

The ornamental design for a case for smart phone, as shown and described.

DESCRIPTION

FIG. 1 is a front perspective view of case for smart phone showing my new design;

FIG. 2 is a rear perspective view thereof;

FIG. 3 is a front elevational view thereof;

FIG. 4 is a rear elevational view thereof;

FIG. 5 is a left side elevational view thereof;
FIG. 6 is a right side elevational view thereof;
FIG. 7 is a top plan view thereof;
FIG. 8 is a bottom plan view thereof;
FIG. 9 is a front perspective view of the upper frame component of the case shown separately for clarity of disclosure;
FIG. 10 is a rear perspective view of the upper frame component of the case shown separately for clarity of disclosure;
FIG. 11 is a front perspective view of the middle frame component of the case shown separately for clarity of disclosure;
FIG. 12 is a rear perspective view of the middle frame component of the case shown separately for clarity of disclosure;
FIG. 13 is a front perspective view of the bottom frame component of the case shown separately for clarity of disclosure;
FIG. 14 is a rear perspective view of the bottom frame component of the case shown separately for clarity of disclosure;

FIG. 15 is an exploded front perspective view showing the components of the case separated for clarity of disclosure; and,

FIG. 16 is an exploded rear perspective view showing the components of the case separated for clarity of disclosure. For clarity of disclosure, the components of the case are shown in isolation in FIGS. 9-14 and separated in FIGS. 15-16. Although the case for smart phone, in which the claimed design is embodied, consists of an upper frame component, a middle frame component, and a bottom frame component, the claim is directed to the overall ornamental appearance of the case in its entirety and does not extend to the ornamental appearance of each of the individual components.

The broken lines throughout the drawing figures depict portions of the case that form no part of the claimed design. The broken lines and unshaded regions form no part of the claimed design.
